UNITED STATES PATENT OFFICE

2,077,576

ELECTRIC SWITCH

George J. Meuer, Milwaukee, Wis., assignor to
Cutler-Hammer, Inc., Milwaukee, Wis., a corporation of Delaware

Application November 9, 1934, Serial No. 752,202

3 Claims. (Cl. 173—322)

This invention relates to improvements in electric switches, and the invention relates more particularly to improvements in electric snap switches of the tool-handle type.

A primary object of the invention is to provide novel means for relieving pulling strains upon the end-wiring terminals of switches of the aforementioned character.

Another and more specific object is to provide 10 a strain relief device in the form of an attachment for switches of known construction.

Another object is to generally improve the 15 details of construction, assembly and operation of the parts of switches of the aforementioned character.

Other objects and advantages of the invention will hereinafter appear.

The accompanying drawing illustrates certain 20 embodiments of the invention which will now be described, it being understood that the embodiments illustrated are susceptible of modification as to certain details of construction thereof without departing from the scope of the appended claims.

25 The snap switches herein disclosed are in general of the character described and claimed in my prior patents, No. 1,889,259, dated Nov. 29, 1933, and No. 1,977,078, dated Oct. 16, 1934, to which patents reference may be had for a more 30 detailed description of certain elements of the switch mechanism.

In the drawing, Figure 1 is a vertical sectional view of an electric snap switch of the end-wiring type, having my improved form of wiring terminal strain-relief applied thereto.

Fig. 2 is an end view of the switch illustrated in Fig. 1.

Fig. 3 is a bottom plan view of the switch shown in Figs. 1 and 2.

40 Fig. 4 is a perspective view of a modified form of strain-relief plate, which may be substituted for that shown in Figs. 1, 2, and 3.

Fig. 5 is a bottom plan view of a switch like that shown in Figs. 1 and 2, but having a modified form of strain-relief plate of the character best illustrated in Figs. 6 and 7.

Fig. 6 is a fragmentary end view of a switch, with the strain-relief plate shown in section to illustrate the manner of inserting the straight bared ends of the circuit wires.

Fig. 7 is a perspective view of the strain-relief plate shown in Figs. 5 and 6, and

55 Fig. 8 is a top plan view of a switch, with certain of the actuating elements removed, and showing a type of wiring requiring a strain-re-

lief plate of the character illustrated in Figs. 1 to 3 or Fig. 4.

Referring first to Figs. 1 to 3, the numeral 15 designates an insulating base which is preferably molded from a phenol formaldehyde condensation product. Said base is recessed from its upper surface to provide a chamber in which are located two pairs of resilient contacts 16, 17 and 18, 19, the tips of which contacts are biased toward each other, as best illustrated in Fig. 1. 10 Interposed between the respective pairs of contact tips at all times is a flat punched plate 20 of insulation, said plate being slidable over the flat upper surface 21 of a rib formed upon the bottom wall of said chamber. Plate 20 is notched at 15 opposite side edges thereof to receive a pair of U-shaped contactors 22 and 23, the arms of each contactor being exposed on opposite sides of said plate. In one extreme position of plate 20 the contactors carried thereby are moved into bridging engagement with the respective pairs of contact tips (Figs. 1 and 8), and in the other extreme position of said plate the contactors are disengaged from said contacts. 20

Superimposed upon plate 20 is a relatively 25 smaller punched plate 24 of insulation, said plates 24 and 22 having registering openings of rectangular contour to receive with a close fit the reduced lower end of a flat punched sheet metal member 25, said reduced lower end being 30 upset over the lower surface of plate 22 to secure said parts to each other. The switch actuating mechanism preferably comprises a wire member 26 of substantially W-form (as shown in detail in my Patent No. 1,977,078), said member being 35 pivotally supported at 27 and 28 by the bulged portion 29 of top plate 29.

Secured to top plate 29 in a well known manner 40 is an externally threaded hollow metal bushing 30, said bushing having aligned openings formed therein to receive a pivot pin 31. Pin 31 is provided with a slightly enlarged intermediate portion (not shown) to provide for a drive fit thereof in an opening formed in the flat punched sheet metal actuating lever 32, said lever being of the desired length and having a ball or knob (not shown) attached thereto with a drive fit. The upper closed end of bushing 30 is provided with a kerf to permit oscillatory movement of lever 32. 45

A coiled compression spring 33 is engaged at 50 its lower end with member 26, the upper end of said spring being provided with a metal cup member to receive an abutment formed at the lower end of lever 32. A relatively thin punched insulating member 34 is interposed between the 55

member 26 and the stationary and movable contact elements of the switch to properly insulate the latter from the former, said member 34 having a slot (not shown) formed therein to 5 provide clearance for member 25. Also as will be apparent, the provision of insulating plate 24 insures a relatively large linear distance between the stationary and movable switch contacts and the member 25, thus increasing the current 10 making and breaking capacity of the switch.

Top plate 29 is secured to base 15 as by means of a pair of screws the shanks of which are shown at 35 and 36, the heads of said screws being located in countersunk recesses in the bottom 15 surface of said base, as shown in my patents aforementioned. The respective stationary contacts of the switch are attached to base 15 at the four corners of the latter and in a plane offset downwardly from the upper surface of said base, 20 as by means of eyelets 37, 38, 39, and 40. Said eyelets also act to secure in position the horizontal portions 41, 42, 43, and 44 of the end-wiring terminal members of the switch, said members having depending vertical portions 25 which are adapted to abut against shoulders formed on the respective ends of the base 15 to prevent inward bending of said vertical portions as an incident to tightening of the respective binding screws. Binding screws 45, 46, 47, 30 and 48 are located adjacent to the lower ends of the vertical portions of the terminal members, and base 15 is provided with recesses to afford clearance for the shanks of said screws. A flat punched plate 49 of insulation is interposed 35 between the upper surface of base 15 and top plate 29 to properly insulate the latter from the aforementioned wiring members.

In wiring a switch of the character herein described it is frequently necessary or desirable to 40 employ relatively large gage solid wires of the character illustrated, whereas upon bending of said wires or upon pulling of the same (or any type of wire) endwise of base 15 an undesirable strain is placed upon the vertical portions of the 45 wiring terminal members, with resultant liability of outward bending or distortion of the latter. To overcome this difficulty in a simple and economical manner, I provide a flat punched insulating plate 50 which is provided with a pair of relatively large substantially circular openings 51, 52, 53, and 54. The arrangement of said openings is preferably 50 such that upon seating of plate 50 against the lower surface of base 15, the circularly looped ends of the wires may be inserted upwardly through the respective openings at a sufficient outward angle to clear the lower end of base 15 and the lower extremities of the terminal members. The wire ends are then positioned vertically as shown in full lines in Figs. 1 and 2 to bring the respective loops in alignment with the 60 tapped openings in said terminal members. The aforementioned binding screws are then applied to mechanically and electrically connect the wire 65 ends to the terminal members.

If the wire ends are bared to the proper length, the shoulders formed by the ends of the respective wire sheaths will act to restrain plate 50 70 against vertical displacement. In ordinary usage, however, it is desirable to provide a substantially right angled bend in each wire, as shown in dotted lines in Fig. 1. In order to prevent endwise displacement of plate 50 relatively to base 15 I prefer to provide the former with

an opening 55 to accommodate a substantially rectangular projection 15^a formed on the lower surface of said base. Thus upon bending of the several wires in the manner indicated in dotted lines in Fig. 1 the outer edges of the respective 5 openings 51 to 54 will act as snubbing shoulders to prevent transmission to the terminal members of any bending or outward pulling strains upon the wires, the interlock between plate 50 and projection 15^a assisting in the performance 10 of this function. Moreover, it will be apparent that outward bending of the several wires will serve to securely clamp plate 50 against the bottom surface of base 15.

The modified form of wiring terminal strain-relief plate 50^a shown in Fig. 4 is provided with the aforescribed openings 51 to 54, inclusive, and the same is additionally provided with a pair of openings 56 and 57 which are adapted to receive the shanks of a pair of securing screws 20 (not shown) which are relatively longer than the screws 35 and 36 aforementioned. The heads of said longer screws are adapted to engage the lower surface of plate 50 to provide for factory assembly thereof whereby the same is retained 25 in seated position against the lower surface of base 15 independently of the circuit wires.

In Figs. 5, 6, and 7 I have shown a wiring terminal strain-relief plate 58 which is provided with openings 55, 56, and 57 like those shown in Fig. 4. However, plate 58 is provided with two pairs 59, 60, 61, and 62 of relatively small circular openings, which pairs are offset inwardly from diagonally opposite corners of the plate. Said openings are just sufficiently large 30 to provide for upward insertion of the straight bared ends of the respective circuit wires 63, 64, 65, and 66, and said openings are so arranged 35 as to insure positioning of the wire ends at the left-hand sides of the respective screw shanks (Fig. 6). With this arrangement the binding screws need not be entirely removed from the terminal members to permit insertion of the wire ends, whereas upon tightening of the screws the wire ends are securely clamped by the screw 40 heads in mechanical and electrical contact with the respective terminal members.

The walls of the respective openings 59 to 62, inclusive, serve as snubbing shoulders upon bending of the several wires in the manner indicated 50 in dotted lines in Fig. 1, whereby the downwardly extending portions of the several terminal members are relieved of outward bending strains as an incident to an outward pull upon the circuit wires. As aforesigned, the opening 55 in plate 55 58 is adapted to accommodate the projection 15^a on the bottom surface of base 15. It is to be understood, of course, that the shorter length screws 35 and 36 of Figs. 1 and 2 may be substituted for the screws 67 and 68 in Figs. 5 and 6, 60 to provide for support of plate 58 solely by the circuit wires upon bending of the latter, the walls of opening 55 cooperating with projection 15^a in such case to prevent displacement of plate 58 65 longitudinally of base 15.

What I claim as new and desire to secure by Letters Patent is:

1. In an electric switch, in combination, a molded insulating base, a punched and stamped sheet metal terminal member having a flat portion thereof secured to said base in a plane offset downwardly from and parallel to the upper surface of the latter, said member having another portion thereof extending downwardly at right angles to said first mentioned portion and

- adapted to seat against one end of said base, a wiring terminal screw having threaded engagement with said downwardly extending portion, said base having a recess to accommodate the shank of said screw, a flat punched plate of insulation underlying said base and restrained against movement relatively thereto, said plate having an opening formed therein to provide for upward insertion of a bared wire end, whereby 5 said wire end may be clamped by the head of said screw, and the wall of said opening providing a snubbing shoulder for said wire to insure against outward displacement of said downwardly extending portion in the event of a pull upon said 10 wire in a direction outwardly from said end of the base.
2. In an electric snap switch of the tool-handle type, in combination, a molded insulating base having a plurality of wiring terminal members 15 each having a portion thereof secured to said base in a plane offset downwardly from and parallel to the upper surface thereof and each also having a portion bent downwardly at substantially right angles to the first mentioned portion 20 thereof to lie against an end wall of said base, a wiring terminal screw carried by each of said downwardly bent portions, a flat punched plate of insulation material underlying said base and restrained against movement relatively to the latter in a given plane, said plate having a plurality 25 of openings formed therein, said openings being respectively adapted to provide for upward insertion of individual wire ends for clamping thereof by the heads of said screws, and the walls 30 of said openings providing shoulders over which the wires may be bent to extend in a plane substantially parallel to said plate, said shoulders acting as snubbers to relieve any bending strains upon said terminal members as an incident to a 35 pull upon any or all of said wires in the aforementioned plane thereof.
3. In an electric snap switch of the tool-handle type, in combination, a molded insulating base 40 having a plurality of wiring terminal members secured to and depending from the upper surface thereof at the respective ends of the base, wiring terminal screws having threaded engagement with said members at the lower ends thereof respectively, said base having a projection formed 45 on the lower surface thereof, a flat punched plate of insulation material underlying said base, said plate having an opening to accommodate said projection and the walls of said opening being adapted to cooperate with said projection to 50 prevent substantial displacement of said plate in the normal plane of the latter, said plate having a plurality of openings formed therein to provide for upward insertion of the bared ends of a corresponding 55 number of circuit wires for clamping of the latter by the heads of the respective terminal screws, the walls of said openings respectively providing shoulders whereby said wires may be bent to extend from opposite ends of said base 60 in a plane substantially parallel to the lower surface of the latter, and said shoulders acting to relieve strains upon said terminal members as an incident to a pull upon the respective wires in the plane aforementioned.
4. In an electric snap switch of the tool-handle type, in combination, a molded insulating base 65 having a plurality of wiring terminal members secured to and depending from the upper surface thereof at the respective ends of the base, wiring terminal screws having threaded engage- 70
- ment with said members at the lower ends thereof respectively, said base having a projection formed on the lower surface thereof, a flat punched plate of insulation material underlying said base, said plate having an opening to accommodate said projection and the walls of said opening being adapted to cooperate with said projection to prevent substantial displacement of said plate in the normal plane of the latter, said plate having a plurality of openings formed therein and adapted upon assembled positioning thereof with respect to said base to provide for upward insertion of the bared ends of a corresponding number of circuit wires for clamping of the latter by the heads of the respective terminal screws, the walls of said openings respectively providing shoulders whereby said individual wires may be bent to extend from opposite ends of said base in a plane substantially parallel to the lower surface of the latter, said shoulders acting to relieve strains upon said terminal members as an incident to a pull upon the respective wires in the plane aforementioned, and means independent of said wires for initially retaining said plate in assembled relation to said base. 75
5. As an article of manufacture, a wiring terminal strain-relief attachment for electric snap switches of the end-wiring type, said attachment consisting of a flat punched plate of insulation adapted to underlie the insulating base of a switch, said plate having a plurality of pairs of openings formed therein adjacent to the opposite ends thereof to provide for upward insertion of the bared ends of circuit wires in definite alignment with the wiring terminals, and said openings respectively providing snubbing shoulders against which the individual wires may be bent to thereby substantially eliminate any outward pulling strains upon the respective wiring terminal members to which said wires are attached. 80
6. As an article of manufacture, a wiring terminal strain-relief attachment for electric snap switches of the end-wiring type, said attachment consisting of a flat punched plate of insulation adapted to underlie the insulating base of the switch, said plate having a centrally located substantially rectangular opening formed therein to accommodate a correspondingly shaped projection formed on the switch base, said plate having a pair of openings formed therein adjacent to each end thereof and offset inwardly from diagonally opposite corners of said plate, said pairs of openings being only sufficiently large to provide for upward insertion of the straight bared ends of circuit wires employed with said switch, the walls of said pairs of openings respectively providing snubbing shoulders to relieve any outward pulling strains upon the switch terminal members as an incident to pulling of the individual circuit wires in directions away from the opposite ends of the base, and said plate having an additional pair of openings formed therein, said last mentioned openings providing clearance for the shanks of the securing screws of the switch the heads of which screws clampingly engage said plate to provide for retention thereof in assembled relation to the switch base. 85
7. As an article of manufacture, a wiring terminal strain-relief attachment for electric snap switches of the end-wiring type, said attachment consisting of a flat punched plate of insulation adapted to underlie the insulating base of a switch, said plate having a pair of openings formed therein and located inwardly a substan- 90

tial distance from the respective ends thereof, said openings being adapted for cooperation with the usual securing screws of the switch to provide for retention of said plate in assembled relation to the switch base, said plate also having a plurality of pairs of openings formed therein adjacent to the opposite ends thereof to respectively provide for upward insertion of the bared ends of individual circuit wires, the walls of said last mentioned openings providing snubbing shoulders against which the respective wires are bent to thereby relieve any outward pulling strains upon the respective wiring terminal members to which said wires are attached.

8. As an article of manufacture, a wiring terminal strain-relief attachment for electric snap switches of the end-wiring type, said attachment consisting of a flat punched plate of insulation adapted to underlie the insulating base of a switch, said plate having a substantially centrally

located opening formed therein to accommodate a correspondingly shaped projection on the switch base, said plate having a pair of openings formed therein respectively adjacent to opposite ends of said central opening, said last mentioned openings being adapted for cooperation with the usual securing screws of the switch, to provide for retention of said plate in assembled relation to the switch base, said plate also having a plurality of pairs of openings formed therein, each pair being located adjacent to one end of said plate to respectively provide for upward insertion of the bared ends of individual circuit wires, the walls of said last mentioned openings providing snubbing shoulders against which the respective wires are bent to thereby relieve any outward pulling strains upon the respective wiring terminal members to which said wires are attached. 15

GEORGE J. MEUER. 20
